(57) **CLAIM**

The ornamental design for a display screen or portion thereof with icons, as shown and described.

DESCRIPTION

FIG. 1 is a front view of a display screen or portion thereof with icons, showing the first embodiment of the new design in a portrait mode; and,

FIG. 2 is a front view of a display screen or portion thereof with icons, showing the second embodiment of the new design in a landscape mode.

The broken line showing of the remainder of the display screen in each drawing is for environmental purposes only and forms no part of the claimed design.

1 Claim, 1 Drawing Sheet
